(57) **CLAIM**

We claim the ornamental design for a combined artificial nail and application tab, substantially as shown and described.

DESCRIPTION

FIG. 1 is a front perspective view of a combined artificial nail and application tab showing the new design;

FIG. 2 is a top plan view thereof;

FIG. 3 is a left side view thereof, the opposite side right view being a mirror image thereof; and,

FIG. 4 is a cross sectional view taken along line 4-4 in FIG. 3. The application tab being fragmentarily shown for convenience of illustration.

The broken lines shown in the drawings illustrate a portion of the combined artificial nail and application tab and form no part of the claimed design.
